UNITED STATES PATENT OFFICE

2,233,630

ENGINE

Frederick H. W. Miller, Napa, Calif.

Application February 21, 1939, Serial No. 257,673

2 Claims. (Cl. 74—60)

My invention relates to improvements in an engine, and it consists of the combinations, constructions and arrangements hereinafter described and claimed.

5. An object of my invention is to provide an engine in which four cylinders are arranged in the same horizontal plane and thus vertical vibration is eliminated during the operation of the engine. The four cylinders are positioned in two groups 10 and the two cylinders in each group are aligned with each other and are also arranged in opposed relation. The pistons in each pair of cylinders are connected together and are also operatively connected to a swash plate which in turn is secured to the motor shaft at an angle. The operation of the pistons will impart a rotative movement to the swash plate and this in turn will rotate the shaft.

The engine is designed primarily for use in 20 airplanes and it may be placed in the airplane wing. Since the four cylinders are arranged in a horizontal plane, the head resistance offered by the engine will be at a minimum and it will not be necessary to increase the thickness of the 25 plane wing in order to accommodate the engine. The engine takes about one-fourth the head-on space occupied by another engine delivering the same amount of horse power. The thrust of the engine caused by the reciprocating pistons will 30 be in the direction of the greatest width of the airplane wing. This thrust may be reduced to a negligible amount if two of the engines are connected in tandem to a single engine shaft. When the two engines are thus connected, a thrust from 35 one of the engines in one direction due to the firing stroke in one of the cylinders will be off-set by a thrust of the other engine in the opposite direction due to the firing stroke in one of its cylinders.

40. The pistons carry piston rods that are rigidly connected thereto and this eliminates the use of wrist pins and further eliminates piston slap. There is less weight per horse power in the device because the cylinders can be made shorter 45 due to the fact that there is no crank shaft and the piston skirt is eliminated.

Other objects and advantages will appear in the following specification, and the novel features of the device will be particularly pointed out in 50 the appended claims.

My invention is illustrated in the accompanying drawings forming a part of this application, in which:

Figure 1 is a horizontal section through the 55 device taken along the line 1—1 of Figure 3;

Figure 2 is a vertical section along the line 2—2 of Figure 3;

Figure 3 is a section along the line 3—3 of Figure 2;

Figure 4 illustrates the firing order of the various cylinders; and

Figure 5 diagrammatically shows two of the engines connected in tandem and mounted in an airplane wing.

In carrying out my invention I provide four 10 cylinders indicated at A, B, C and D in Figure 1. The cylinders A and C are mounted in opposed relation and are secured to a housing or casing indicated generally at 1. The cylinders B and D are likewise mounted in opposed relation and are 15 secured to the same housing. The cylinders A and B are considered front cylinders and the cylinders C and D are rear cylinders. A piston 2 is mounted in each cylinder and it will be noted that each piston is not provided with the usual 20 piston skirt. Connecting rods 3 are rigidly secured to the pistons 2 in the cylinders B and C. The free ends of the two piston rods 3 are provided with cross heads 4 and these cross heads are slidably mounted in channel shaped guides 5, 25 see Figure 3, the guides carrying flanges 5a on one of their sides to provide a slot 5b. The pistons 2 that are in the cylinders A and D carry piston rods 6 that are rigidly connected thereto and are pivotally connected at 7 to the cross 30 heads 4.

The casing 1 rotatably carries a motor shaft 8 and a swash plate indicated generally at E is mounted on the shaft. The swash plate comprises a disc 9 which is secured to the shaft 8 35 by a screw 10 or other suitable fastening means. The disc 9 is disposed at an angle and the opening 10' for the screw extends at right angles to the shaft axis. Ball race grooves 9' and 12' are formed in both peripheral side edges of the disc. 40 A ring 11 that encircles the periphery of the disc has a ball race groove 11' that cooperates with the ball race groove 12' and receives ball bearings 12. An adjusting collar 13' is threaded into the ring 11 and has a ball bearing race 13a cooper- 45 ating with the adjacent ball race groove 9' in the disc 9 for receiving additional ball bearings 12. All of the ball bearings in both groups will transmit rotational force from the ring 11 to the entire circumference of the disc 9. The ring 11 carries 50 trunnions 13 which are slidably received in sleeves 14 and it will be noted from Figure 1 that the sleeves are rotatably mounted in the cross heads 4. A reciprocation of the pistons 2 in the cylinders will cause the cross heads to reciprocate 55.

in the guides and to rock the ring 11 back and forth. This rocking movement of the ring will impart a rotative movement to the disc 9 and thus cause the shaft 8 to rotate.

5 I will now describe the means for delivering a combustible mixture to the cylinders in proper sequence and for exhausting the burned gases from the cylinders in order to cause the pistons in the cylinders to operate on the four cycle principle. In Figure 2 I show intake valves 15 on the lower sides of the cylinders A to D inclusive, and exhaust valves 16 on the upper sides of the same cylinders. In Figure 3, I show an "intake" cam gear 17 and an "exhaust" cam gear 18, meshing 10 with a drive gear 19 which in turn is secured to the motor shaft 8. The ratio between the gears 17, 18 and 19 is such as to cause the cam gears 17 and 18 to rotate at one-half the speed of the engine shaft 8. The cam gears 17 and 18 are enclosed in a housing 20 that forms a part of the casing 1.

15 In Figure 2 I show intake tappets 21 extending from both sides of the lower portion of the casing 20 and exhaust tappets 22 extending from both 25 sides of the upper portion of the cam casing. Since all of the tappets are identical, I have shown only one tappet in cross section in Figure 2 and a description of this one will suffice for all. The exhaust tappet 22 shown in section consists 30 of a sleeve that is integral with the casing 20 and acts as a guide for a tappet plunger 23. A cam follower, consisting of a roller 24 is rotatably carried by the plunger 23 and rides on the face of the cam gear 18. A tappet rod 25 extends from 35 the plunger 23 to a rocker arm 26 which in turn is rotatably mounted on a supporting rod 27. The rod 27 is supported by arms 28 which in turn are connected to the cylinders C and D. The rocker arm 26 bears against the stem 16a of the exhaust 40 valve 16.

45 The cam 17 has two arcuate cam portions on one side and two arcuate portions on the opposite side. In Figure 3 I have indicated the intake tappets 21 for the front cylinders A and B and therefore these tappets may be referred to as A21 and B21. It will be noted that the roller 24 of the tappet A21 is disposed further away from the center of the cam gear 17 than is the roller 24 of the tappet B21. The undersurface of the cam 50 gear 17 when looking at Figure 3 is provided with cam portions A17 and B17 for engaging with the cam followers on the tappets A21 and B21. In like manner, the front face of the cam follower 17 has cam portions C17 and D17 for engaging with 55 the cam followers on the tappets 21 connected with the intake valves 15 in the rear cylinders C and D. When the cam gear 17 is rotated, the intake tappets will be actuated to operate the intake valves 15 in all four cylinders in proper sequence.

60 The exhaust cam gear 18 is provided with cam portions A18 and B18 on one face and with cam portions C18 and D18 on the opposite face. These 65 cam portions are arranged to actuate the exhaust valves 16 in all four cylinders in proper sequence. In Figure 4 I show the firing order for the four cylinders A to D inclusive. I further indicate the movement of the connecting rods 3 and 6 and 70 what takes place in all four cylinders during the four cycles. It will be noted that the left-hand diagram in Figure 4 shows the cylinder C firing, and the next diagram shows the cylinder A firing. The third diagram from the left shows the cylinder B firing and the last diagram shows the cylinder 75

5 cylinder D firing. The firing order of the four cylinders therefore follows a clockwise rotation around the four cylinders. It will further be noted that the firing of cylinder C in the left-hand diagram 10 will cause the piston in this cylinder to move in the direction of the arrow and to move the piston in the cylinder A during its compression stroke. In this way, part of the horizontal thrust created by the firing in the cylinder C will be absorbed by the piston in the cylinder A moving through its 10 compression stroke.

15 In order to completely absorb the horizontal thrust created by the firing in any one of the four cylinders, I can mount two engines in tandem as shown in Figure 5. The firing order of the two engines is so arranged that when the cylinder B in the front engine is firing, for example, the cylinder C in the rear engine will also be firing. Both engines are connected to the common engine shaft 8 and therefore the two thrusts exerted 20 by the pistons during the firing strokes will balance each other. The arrangement of the cylinders in a horizontal plane eliminates vertical vibration and the use of two engines connected in tandem and fired in the manner just described, 25 will eliminate horizontal vibration. The arrangement of two engines in tandem is therefore highly desirable for use in airplanes. In Figure 5 I show two sets of tandem engines mounted in the wings 29 of an airplane 30. The shafts 8 of both 30 sets of tandem engines are directly connected to propellers 31.

35 From the foregoing description of the various parts of the device, the operation thereof may be readily understood.

40 It is not necessary to show the ignition circuits for the spark plugs 32 nor is it necessary to describe any particular oil circulating mechanism for removing oil from the housing 1 through an oil outlet pipe 33, see Figure 2, and for delivering the oil into the top of the housing through two oil inlet pipes 34. It will be noted that the pipes 34 are arranged on opposite sides of the swash plate E and oil will drop from the pipes 34 directly onto the shaft 8. The rotation of the shaft 8 will throw the oil by centrifugal force into the cross head guides 5 and from there the oil will be thrown into the bottoms of all four of the cylinders A to D inclusive, by the reciprocation of the cross heads 4 and the piston rods 3 and 6. The oil will drain from the cylinders back into the lower portion of the housing 1 and thus complete the oil circuit.

45 The four cylinders will fire in the manner 55 shown in Figure 4 and the intake cam 17 and the exhaust cam 18 will actuate the intake and exhaust valves in proper order to cause each piston to move through a standard four cycle movement. The arrangement of the cylinders 60 in a horizontal plane does away with vertical vibration. The head-on space occupied by the engine is reduced to practically one-fourth the space occupied by a standard airplane engine, due to the particular arrangement of the four 65 cylinders in a single horizontal plane. The connecting rods 3 and 6 are rigidly secured to their respective pistons and the rods 6 are pivotally connected to the cross-heads 4 to permit a slight angular movement between aligned pistons should 70 the opposed cylinders not be directly in alignment with each other. It will be noted that I eliminate wrist pins and this does away with connecting rod slap. Low pressure oiling is used and the oil merely drops onto the shaft 8. The swash 75

plate E permits the force of the explosion to be more quickly delivered to the shaft 8 for rotating the shaft and this is due to the fact that the connecting rods 3 and 6 are rigidly secured to the pistons. Wear on the double thrust bearings can be taken up by adjusting the collar 13' for simultaneously altering the widths of both ball bearing raceways.

While I have shown only the preferred form 10 of my invention, it should be understood that various changes or modifications may be made within the scope of the appended claims without departing from the spirit of the invention.

I claim:

15 1. An engine comprising a shaft, a swash plate including a disc rigidly secured to the shaft and extending at an angle to the shaft axis, a ring rotatably mounted on the disc, there being a rotative connection throughout the entire adjacent circumferences of the disc and ring, radially-extending trunnions carried by the ring, sleeves having transverse bores for slidably and rotatably receiving the trunnions, cross-heads having bores for rotatably receiving the sleeves, parallel guides 20 for slidably receiving the cross-heads, cylinders 25

disposed at the ends of the guides and having their axes lying parallel therewith, pistons slidably mounted in the cylinders, and connecting rods rigidly connected to the pistons, one connecting rod of each pair of pistons being rigidly secured to its cross-head and the other connecting rod being pivotally secured to the same cross-head.

2. A swash plate for an engine comprising a disc having a shaft-receiving bore therein extending at an angle, said disc having a screw-receiving bore extending at right angles to the shaft axis, said disc also having a double groove ball bearing raceway formed at its peripheral corner edges, a ring enclosing the disc periphery and being provided with a ball bearing groove raceway cooperating with one of the disc grooves for receiving ball bearings, a collar threaded into the ring and formed with a ball bearing raceway 15 cooperating with the other disc groove, ball bearings placed in the cooperating raceways, said ring carrying radially-extending trunnions designed to be operatively connected to the pistons. 20

FREDERICK H. W. MILLER. 25
